WEATHER WINDOW SHADE

Henry Van Der Horst, Chicago, Ill.

Application August 27, 1952, Serial No. 306,565

6 Claims. (Cl. 160—368)

1

This invention relates to window shades of the type in which the edges are substantially sealed in relation to the frame of a window in which the shade is positioned, and in particular a window shade having enlarged hems or tunnels providing sleeves at the sides and in which eccentrically mounted pins extended through said tunnels are rotated to clamp the edges of the shade against the inner surfaces at the sides of the window frame.

The purpose of this invention is to provide means for continuously sealing the edges of a window shade in relation to a window frame in which the shade is positioned.

Various attempts have been made to hold the edges of window shades to prevent rays of light and also circulation of air passing through the window, however, owing to the material of which window shades are formed it is difficult to grip the edges without tearing the shade when excessive loads, such as resulting from high winds, contact the shade. With this thought in mind this invention contemplates forming continuous tunnels on the edges of window shades whereby the gripping or holding load is applied continuously throughout the length of the shade and wherein the holding means is accomplished by clamping the shade against the inner surface of a window frame.

The object of this invention is, therefore, to provide an improved window shade mounting wherein eccentrically mounted rods extended through tunnels at the sides of a window shade are actuated to retain the shade in clamping relation with a window frame.

Another object of the invention is to provide means for mounting a window shade having tunnels on the edges whereby the tunnels are adapted to be rolled on a shade roller in the upper part of the window.

A further object of the invention is to provide an improved shade mounting wherein a shade is held continuously along the side edges and in which the mounting is of a simple and economical construction.

With these and other objects and advantages in view the invention embodies a window shade mounting having a conventional shade roller encased in a housing at the upper end of a window frame with a shade on the roller in which the shade is provided with continuous tunnels at the sides and across the lower end and in which the edges of the shade are held with eccentrically mounted pins which extend upwardly into the tunnels, the upper ends of the pins having eccentrically positioned extensions of reduced di-

2

ameter and the lower ends having arms connected through springs to a lever pivotally mounted on the window sill.

Other features and advantages of the invention will appear from the following description taken in connection with the drawings, wherein:

Figure 1 is a front elevational view illustrating a window having the improved weather shade installed therein showing the shade drawn downwardly to a point spaced from the window sill.

Figure 2 is a similar view showing the shade moved upwardly and with the eccentric pins turned so that the shade is released from clamping relation with the sides of the window frame.

Figure 3 is a sectional plan through the window taken on line 3—3 of Fig. 1 with the parts shown on an enlarged scale and showing the positions of the parts with the edges of the shade clamped against the inner surface of the window frame.

Figure 4 is a vertical section through a window frame showing the improved weather sealing shade with the parts shown on an enlarged scale, and with parts broken away.

Figure 5 is a sectional plan through one side of the window frame taken on line 5—5 of Fig. 4 illustrating one of the tunnels at the edge of a shade with the tunnel partially flattened and passing between rollers.

Figure 6 is a plan view showing the upper end of one of the pins which extends through the tunnels of the shade.

Figure 7 is a side elevational view of one of the eccentric pins with parts broken away and with parts shown in section.

Figure 8 is a plan view illustrating one of the bearing plates for holding the lower end of an eccentric pin.

Figure 9 is a side elevational view of the plate shown in Fig. 8.

Figure 10 is a plan view illustrating a modification and showing a bearing plate with a continuous slot for the screws to provide adjustment.

Figure 11 is a detail showing a shade roller clip or bracket positioned in a recess in the window frame.

Figure 12 is a longitudinal section taken on line 12—12 of Fig. 11 also illustrating the recess with the shade holding clip therein.

Figure 13 is a sectional plan through the lower part of the window, taken substantially at the point indicated by the line 3—3 on Figure 1, illustrating a modification wherein the operating elements of the pins on which the shade slides are incorporated in the window sill.

Figure 14 is a detail showing a section through

the window sill of the design shown in Figure 13.

Referring now to the drawings wherein like reference characters denote corresponding parts the improved weather shade of this invention includes a shade 10 having sleeves or tunnels 11 and 12 at the sides with a tunnel 13, for a window stick, extended across the lower end, eccentric pins 14 and 15, pivotally mounted on studs 16 on bearing plates 17, said eccentric pins having noneccentric pins 18 extended from their upper ends, rollers 19 and 20 positioned to engage side surfaces of the pins 18 for supporting the upper ends of the pins, and a hand lever 21 pivotally mounted by a pin 22 on the window sill 23 and connected to arms 24 and 25 extended from the lower ends of the pins 14 and 15 by rods 26 and 27 with springs 28 and 29 extended around the rods and positioned to urge the arms 24 and 25 outwardly away from the center wherein sections of the pins 14 and 15 clamp the edges of the tunnels 11 and 12 against the inner surfaces of a window frame 30.

The pins 14 and 15 are provided with eccentrically positioned bores 31 and the studs 16 extend into the lower ends of the bores whereby as the pins 14 and 15 are rotated on the bearing plates 17 the larger radius clamps sections of the pins against the inner surfaces of the side members of the window frame.

The window sill 23 is provided with studs 32 and 33 against which the ends of the springs 28 and 29 are positioned and with the parts released as illustrated in Fig. 3 the springs urge the arms 24 and 25 outwardly away from the center of the sash, to the position shown in Fig. 3 whereby the sections of the pins 14 and 15, on the larger radius, are urged into clamping relation with the inner surfaces of the window frame. When it is desired to release the window shade the hand lever 21 is moved to the left thereby drawing the arms 24 and 25 inwardly with the pins 14 and 15 turned to the position shown in Fig. 2 whereby the sides of the shade are released from clamping relation with the inner surfaces of the window frame.

The rollers 19 and 20, between the eccentrically positioned pins 18 at the upper ends of the pins 14 and 15 are positioned or journaled on shanks 34 and 35 of screws 36 and 37, respectively and the rollers are positioned, with one at a higher elevation than the other, as illustrated in Fig. 4, to facilitate the hems or tunnels at the edges of the shade passing between the rollers and also to permit the tunnels being flattened as the shade passes around a shade roller 38 at the upper end of the window frame.

The rollers 19 and 20 hold the sections 18 of the pins in alignment with studs 16 on the bearing plates 17, the bearing plates being held by screws 39 to the window sill and the plates being positioned in slots 40, as shown in Fig. 4.

The ends of the shade roller 38 extend into recesses 41 in the sides of the window frame with pins 42 at the ends of the roller held in clips 43 on base plates 44 which are mounted in the recesses 41 with brads 45 or the like. The clips 43 are provided with slots 46 in which the pins 42 are positioned.

The shade roller is preferably covered with a plate 47 that is secured to the window frame with fasteners 48.

The bearing plates 17 may be replaced with similar bearing plates 49, as shown in Fig. 10, the plate 49 being provided with studs 50, similar to the studs 16 and with elongated slots 51 through which screws similar to the screws 39

may be placed whereby the eccentrics of the pins 14 and 15 are readily adjustable.

With the parts mounted in this manner the hand lever 21 is turned on the pivot 22 whereby the rods 26 and 27 draw the arms 24 and 25 toward the center moving the sections of the pins 14 and 15 on the large radius through an angle of substantially 90 degrees whereby the surfaces of the pins move away from the sides of the window frame to the positions illustrated in Fig. 2 and the shade is released so that it may be moved upwardly and downwardly. When the shade is in the desired position the lever 21 is released and the springs 28 and 29 urge the arms 24 and 25 outwardly whereby the sections of the pins 14 and 15 on the large radius clamp the edges of the shade against the inner surfaces of the window frame.

With the rollers 19 and 20 positioned as illustrated in Figs. 4 and 5 the tunnels at the sides of the window shade collapse and bulge outwardly through the rollers whereby the tunnels are flattened as the shade passes over the shade roller 38.

The operating parts including the lever 21, springs 28 and 29 and cables 26 and 27 are protected by a cover 52, as shown in Figure 4. The cover is spaced above the window sill by a flange 53 at the front.

In Figures 13 and 14 the operating parts including the lever 54, similar to the lever 21, springs 55 and 56, and cables 57 and 58 are incorporated in a window frame 59 below a sill 60 and pins 61 and 62 similar to the pins 14 and 15 extend upwardly through openings in the window sill. By this means the operating parts are hidden and the parts are actuated by an extended end 63 of the lever 54, the end 63 of which extends through a slot 64 in the window frame. The pins 61 and 62 are provided with extensions 65, to which the operating parts are connected as shown in Figure 14.

It will be understood that modifications, within the scope of the appended claims, may be made in the design and arrangement of the parts without departing from the spirit of the invention.

What is claimed is:

1. A weather window roll shade comprising a sheet of material having tunnels on the edges, pins eccentrically mounted in the sides of a window frame with the upper ends of the pins extending into the tunnels at the sides of said sheet of material, and means for rotating the pins for clamping the tunnels at the sides of said sheet of material against the inner surfaces of the window frame in which the shade is positioned.

2. A weather window roll shade having tunnels at the edges, pins eccentrically mounted in the side of a window frame with the upper ends of the pins extending into the tunnels at the sides of said shade, resilient means for rotating the pins for clamping the edges of the shade against the inner surfaces of the window frame, and means for manually rotating the pins to release the edges of the shade from the window frame.

3. A weather window roll shade having tunnels at the edges, pins eccentrically mounted in the side of a window frame with the upper ends extending into the tunnels at the sides of said shade, resilient means for rotating the pins for clamping the edges of the shade against the inner surfaces of the window frame, means for manually rotating the pins to release the edges of the shade from the window frame, and guide roll-

5

ers mounted on the window frame and positioned on opposite sides of the upper ends of the pins and retaining the upper ends of the pins in alignment with the mounting means of the lower ends thereof.

4. A weather window roll shade having tunnels at the sides and across the lower end, spaced parallel vertically disposed pins, means pivotally mounting the lower ends of the pins eccentrically of the longitudinal axes thereof, the pins extending upwardly into the tunnels at the sides of the shade, each pin having a noneccentric section in extension of its upper end, a pair of rollers journaled on each side of the window frame and engaging opposite sides of said non-eccentric sections providing journalling means for the upper sections of said pins and passage means for said tunnels, resilient means actuating the pins for clamping the material of the tunnels against the inner surfaces of the window frame and means for manually actuating the pins whereby the surfaces thereof are spaced from the inner surface of the window frame against the action of said resilient means for unclamping said tunnels.

5. A weather window roll shade having tunnels on the edges, pins eccentrically mounted in the side of a window frame with the upper ends extending into the tunnels at the sides of said shade, resilient means for rotating the pins for clamping the edges of the shade against the inner surfaces of the window frame, means for manually rotating the pins to release the edges

6

of the shade from the window frame, means for mounting the pin rotating means on the sill of the window frame, a cover enclosing said pin rotating means, and guide rollers mounted on the window frame and positioned on opposite sides of the upper ends of the pins and retaining the upper ends of the pins in alignment with the mounting means of the lower ends thereof.

6. A weather window roll shade having tunnels at the edges, pins eccentrically mounted in the side of a window frame with the upper ends extending into the tunnels at the sides of said shade, resilient means for rotating the pins for clamping the edges of the shade against the inner surfaces of the window frame, means for manually rotating the pins to release the edges of the shade from the window frame, means for mounting the pin rotating means in the frame of the window with said rotating means positioned below the sill of the window frame and guide rollers mounted on the window frame and positioned on opposite sides of the upper ends of the pins and retaining the upper ends of the pins in alignment with the mounting means of the lower ends thereof.
